[57] CLAIM

The ornamental design for a combined ring and article holder, as shown and described.

DESCRIPTION

FIG. 1 is a top view of a combined ring and article holder showing my new design;

FIG. 2 is a right side view;

FIG. 3 is a bottom view;

FIG. 4 is a front view;

FIG. 5 is a left side elevational view, the broken line showing of a writing implement being illustrative of environment only.
